CONFLAGRATION-RETARDATIVE CURTAIN

Paul Rhoads Wagner, San Diego, Calif.

Application November 6, 1942, Serial No. 464,701

2 Claims. (Cl. 160—120)

My invention relates to improvements in conflagration-retardative curtains in which a plurality of portable sections of fire-resistant curtains are employed to cover the roof and side of a building which adjoin a conflagration; and the objects of my improvement are, first, to prevent the spread of conflagration by protecting buildings from being set afire by sparks and flame from an adjoining fire; second, to provide fire-resistant curtains composed of a plurality of sections, each section being capable of being rolled up into a compact bundle and capable of being carried up ladders onto the roof of any building that adjoins a blazing fire; third, to afford means for quickly fastening a taut line across a roof onto which line the sections of curtains are capable of being fastened; fourth, to provide means for overlapping the edges of a plurality of curtain sections so that they form a complete protective curtain; fifth, to aid the war effort by retarding and preventing the spread of conflagration, especially in army and naval concentrations where buildings are of combustible materials, and in congested residential areas, in bungalow courts, in lumber yards and like places where the spread of fire is probable and the job of preventing the fire from spreading to adjoining structures and materials is difficult.

I attain these objects by the mechanism illustrated in the accompanying drawing, in which

Figure 1 is a view in perspective of the entire device as it covers a portion of a building; Fig. 2 is a detailed view in perspective of one section of the curtain as it appears when rolled up for storage purposes and ready for being transported and carried up to any roof; Fig. 3 is a detailed view in perspective of two sections of the curtain as they appear when partly unrolled and overlapped; Fig. 4 is a view of the hooks, cable, and cable-clamp, as they appear when the cable is stretched taut across the roof of a building; and Fig. 5 is a view of an auxiliary fastening hook for use in holding the cable-hooks and cable if and when the side wall of a building extends above the roof.

Similar numerals refer to similar parts throughout the several views.

The conflagration-retardative curtains 4 consist of a plurality of similar sections (see 4, 4, 4, 4, and 4 in Fig. 1). It is made in sections so that each section 4 can be readily handled by one man and can be carried up a ladder to the roof of a building. The length of section 4 is governed by the kind of buildings for which it

may be designed to protect; two-story barracks and buildings require a longer curtain than is required for a bungalow court or for one-story structures. The width of each section is governed by its weight; although it is desirable to have each section 4 cover as wide a portion of the roof as possible, nevertheless said section must not be too heavy and cumbersome for one man to carry up a ladder. The curtain 4 is made of incombustible materials; no particular incombustible materials are claimed as a part of this invention. One variety of fire-resisting curtain may be made of fly screen coated with lime wash; likewise, a cement wash can be applied to metal screen; in the same manner, a wash made of lime, cement and asbestos can be used. However, I prefer a fire-resistant curtain made of felt, asphalt saturated, reinforced with at least two flexible wires running lengthwise 10 with the curtain, then coated with asphalt and surfaced with slate granules.

A strip of rigid material 5 is fastened across the top end of the curtain section 4 (see Figs. 2 and 5) which strip equalizes the pull of the 15 curtain's weight and prevents tearing. The curtain hooks 6, 6, are fastened to the strip 5 and detachably hook onto the cable 1 (see Figs. 1, 2, and 3).

The cable 1 is detachably fastened across the 20 roof of a building by means of the roof-hooks 2, 2, which are hooked over the outer edges of the roof (see Figs. 1 and 4). One end of the cable 1 is firmly fastened to one of the hooks 2 which is hooked onto the outside edge of the 25 roof and the other end of the cable 1 is slidably passed through the eye of the other hook 2 which is hooked onto the opposite edge of the roof; the cable 1 is pulled taut between the hooks 2, 2, and is fastened in a taut position by means 30 of the cable clamp 3. The curved neck of the hook 2 operates as a fulcrum and sinks the pointed end into the under side of the roof's overhang and thus prevents the hook and cable from slipping downward.

In the event that the fire-threatened building 35 is of the flat roof type of construction with side walls that extend above the roof, the auxiliary fasteners 7, 7, are provided. The fastener 7 is a metal bracket which is placed over the top of a 40 side-wall and has an eye or ring on its inside end into which receptacle the pointed end of the roof hook 2 is detachably inserted (see Fig. 5).

The device may be more fully disclosed by a 45 description of its operation. The rolls of cur-

tains, together with the hooks, cable and ladders should be stored on a vehicle in readiness for quick transportation to the location of a fire which threatens adjoining buildings. The ladders are set to reach the roof on the side of the building away from the fire. At least two ladders should be employed so that one may be used for ascending and the other for descending. The hooks are set on opposite edges of the roof so that the cable lays parallel with the fire and the cable is stretched taut and clamped fast in said position. The upper ends of the sections of curtains are hooked onto the cable one after the other and allowed to unroll down over the side of the building so that edges of the curtains will overlap slightly and thus form a complete protective curtain covering the side of the building exposed to the conflagration. A little practice at naval bases and army camps will make such operation both swift and efficient. After the conflagration has been extinguished, any undamaged and usable sections are rolled up again and stored away with the rest of the equipment for possible future use at another location when needed.

I am aware that prior to my invention, fire-resistant curtains have been made for use inside theater buildings and that other rigid-type of asbestos fire-curtains have been marketed. I therefore do not claim such a combination broadly; but I claim:

1. In a conflagration-retardative curtain, the combination of a plurality of fire-resistant curtain sections being adapted to be rolled up into portable bundles and each section being provided with fastening means on the outside end of the section roll, a cable stretched across the roof of a building and fastened substantially parallel to a side of the building, said fastening means of the sections being attachable at spaced points to said cable, whereby each section roll may unroll itself by gravity and afford part of a protective curtain hanging down a side of the building substantially as set forth.
2. The combination, in a portable fire-resistant curtain, of a plurality of curtain sections being adapted to be rolled up into portable bundles and each section being provided with fastening means on the outside end of the section roll, a cable stretched across the roof of a building and fastened substantially parallel to a side of the building, said fastening means of the sections being attachable at spaced points to said cable so that the outer edge of each section roll will overlap the adjoining section roll, whereby each section roll may unroll itself by gravity and afford part of a curtain hanging down a side of a building as a protection from fire, in manner substantially as herein set forth.

PAUL RHOADS WAGNER.
